UNITED STATES PATENT OFFICE

2,506,396

BRACELET

Emil M. Swanson, Syracuse, N.Y.

Application January 15, 1947, Serial No. 722,214

6 Claims. (Cl. 63—7.)

1

This invention relates to jewelry and in particular to arm bracelets.

It is an object of this invention to provide a bracelet which is formed of a plurality of detachable sections each of which can be worn singly, or sections can be added or removed to provide a bracelet of any desired length.

A related object is to provide a bracelet the length of which the wearer can adjust quickly and easily.

Further objects are to provide a bracelet in accordance with the above objects which is tapered to conform to the contour of the wearer's arm, which is simply and inexpensively manufactured, which presents an attractive appearance and which the wearer can put on or remove with ease.

According to the invention, the bracelet comprises a plurality of split sections detachably joined one to another. Means are mounted on each section to engage the adjoining end portions of the adjacent section and join the two sections together, and complementary means are formed on the end portions of the adjacent sections to secure the engagement. Separate locking means are provided to lock together the split edges of the bracelet sections. When the wearer desires to vary the length of the bracelet, the locking means can be removed and one or more sections detached or added.

Preferably, the bracelet is tapered from its bottom outwardly so as to conform to the contour of a wearer's arm. This is particularly desirable when a number of sections are joined together into a gauntlet type bracelet, such as one extending substantially from the wearer's wrist to the elbow. Also, most suitably, each section is separately hinged so that the bracelet can be put on or taken off the arm easily. While each section may be made of any desired number of segments or parts, depending in some cases upon the size of the arm of a wearer, and may also be made of any desired length and worn singly, the bracelet illustrated in the drawing is made of a plurality of sections each formed of two parts.

The preferred embodiment of the invention is illustrated in the accompanying drawings of which Fig. 1 is a side elevation of the bracelet; Fig. 2 is a perspective view of two adjoining split sections of the bracelet; Fig. 3 to a top view of the bracelet shown in Fig. 1; and Fig. 4 is a view along lines IV—IV of Fig. 2, enlarged to show the details thereof.

Referring to the drawings, a plurality of split ring sections 1 are provided each of which is 55

2

formed of two parts or segments connected together by a hinge 2 of any suitable construction. The sections are joined one to another by pivotally mounting four clasps 3 on the inner surface 5 of the lower end of each section. Inwardly turned flanges 4 are formed on the upper and lower peripheral edges of the sections, and each flange is provided with four pairs of clasp-receiving notches 5 (Fig. 3) placed at like circumferential 10 positions thereon so that, in the assembled bracelet, the notches are in longitudinal alignment. Referring to Figs. 2 and 4, clasps 3 are formed of legs 6 and an enlarged portion 7. The clasps of each section are so positioned that when swung downwardly legs 6 are received by the aligned notches of its end and of the adjacent section, and end portion 7 can be sprung over the flange of the adjacent section to secure the engagement of the two sections. Formed on the inner surface 20 of each section directly above each clasp is a boss 8. When a clasp is not in use it can be swung upwardly and pressed under the boss so as to be caught there and retained out of sight.

Another feature of this invention is the manner 25 in which the split or free edges of the sections are united. Accordingly, eyes 11 are formed on the free edges of the sections and the eyes on one free edge of a section are positioned in staggered relation to those on the other so that when the section is closed the rings interlock in registry 30 to receive a headed locking pin 12. It is apparent that pins 12 must vary in length to conform to the length of the bracelet. This, however, represents little difficulty since such pins are small enough to be carried easily and but a few at the most need be carried.

A further feature is that the bracelet units are tapered, as shown in Fig. 1, to conform to normal arm contour. Such a taper greatly improves the 40 appearance of the bracelets, particularly when the wearer desires a bracelet of sufficient length to extend substantially from wrist to elbow. However, in a tapered bracelet of such a length, it is practically necessary to employ the connecting 45 elements described above, or their mechanical equivalents. As is apparent, such a tapered bracelet is not adapted to be slid over the hand of the wearer and onto the arm. If it were capable of being placed on the arm by such sliding, it would be too large for the wearer and would not present the desired attractive effect. Thus the provision of hinges 2 permit a bracelet of any length to be easily clamped around the arm. Further, the individual hinges for each section as well as the fact that each section is

provided with its own clasping means 3 permit the bracelet to be removed from the arm, sections quickly added or removed, and the revised bracelet replaced. It is also apparent that the free ends of the bracelet must be joined together after the bracket is placed around the arm. Locking pin 12 and eyes 11 provide an inexpensive, attractive and secure means for so joining together these ends.

Other features which greatly enhance the practical value of this bracelet are the simplicity with which its sections can be manufactured and the ease with which they can be fitted to purchasers having unusually small or large arm circumference. The manufacturing steps will be obvious. If desired, the sections can be made in other geometric forms, such as octagonal or hexagonal. In fitting the sections to the purchaser, the jeweler will be provided with a plurality of formed sections graduated evenly from small to large. The purchaser may select the section that fits the wrist and then purchase as many successively larger sections as desired.

According to the provisions of the patent statutes, I have explained the principle, construction and mode of operation of the invention and have illustrated and described what now is considered to be its best embodiment. However, it is to be understood that, within the scope of the appended claims, the invention may be practiced by other forms than those specifically illustrated and described.

I claim:

1. A bracelet comprising a plurality of detachable split sections, said bracelet tapering outwardly from bottom to top to conform to the contour of a wearer's arm, means mounted on each section engaging the end portion of its adjacent section, means formed on said adjacent section to receive said engaging means and secure said engagement, means locking together said split edges of the bracelet sections, and hinge members associated with each section to permit the separate opening and closing of each section whereby said locking means can be removed and the length of the bracelet varied by attaching or detaching one or more of said sections.

2. A bracelet comprising a plurality of detachable two-part hinged sections each having in-turned flanges at its peripheral edges provided with clasp-receiving notches, said bracelet tapering outwardly from bottom to top to conform to the contour of a wearer's arm, a clasp pivotally mounted on the inner surface of each section and formed to engage said notches in the flange of an adjacent section, and means locking together the free edges of said hinged sections, whereby said locking means can be removed and the length of the bracelet varied by attaching or detaching one or more of said sections.

3. A bracelet comprising a plurality of detach-

able two-part hinged sections, said bracelet tapering outwardly from bottom to top to conform to the contour of a wearer's arm, means mounted on one end of each section engaging the end portion of its adjacent section, means formed on said adjacent section to receive said engaging means and secure said engagement, interlocking registering eyes formed on the free edges of said hinged sections, and a pin extending through said eyes to lock together said free edges of the sections, said locking pin being removable and the length of the bracelet varied by attaching or detaching one or more sections.

4. A bracelet comprising a plurality of detachable two-part hinged sections each having in-turned flanges at its peripheral edges provided with clasp-receiving notches, said bracelet tapering outwardly from bottom to top to conform to the contour of a wearer's arm, a clasp pivotally mounted on the inner surface of each section and formed to engage said notches in the flange of an adjacent section, interlocking registering eyes formed on the free edges of said hinged sections, and a pin extending through said eyes to lock together said free edges of the sections, said locking pin being removable and the length of the bracelet varied by attaching or detaching one or more sections.

5. A bracelet comprising a plurality of detachably interconnected segments that taper outwardly from the bottom to the top, the edges of each segment being provided with a plurality of eyes positioned in staggered relation to those of adjacent segments to form registering pin-receiving openings, and pins in said openings pivotally connecting the segments together, said bracelet tapering outwardly in a conical plane from its bottom to its top.

6. A bracelet comprising a plurality of segments that taper outwardly from the bottom to the top to conform to the contour of the wearer's arm, means mounted in each section engaging the end portion of its adjacent section, and means formed on said adjacent section to receive said engaging means and secure said engagement, said bracelet tapering outwardly in a conical plane from its bottom to its top.
